UNITED STATES PATENT OFFICE.

CHARLES L. LILLEBERG, OF CHICAGO, ILLINOIS.

SWITCHING DEVICE.

1,374,085.

Specification of Letters Patent.

Patented Apr. 5, 1921.

Application filed July 25, 1919. Serial No. 313,295.

To all whom it may concern:

Be it known that I, CHARLES L. LILLEBERG, citizen of the United States, residing at Chicago, in the county of Cook and State 5 of Illinois, have invented a certain new and useful Improvement in Switching Devices, of which the following is a full, clear, concise, and exact description.

My invention relates to switching devices 10 and is of particular service where employed in the construction of timers for controlling the occurrence of the ignition sparks that fire the charges in internal combustion engines. The invention, however, is not to be 15 limited to any particular use to which the switch is adapted.

The switching device of my invention includes relatively rotatable contact members each in the form of an arm whose base portion 20 is transverse to the axis of rotation of the rotatable contacting member and whose contacting portion is angular to its base portion, the contacting portions of the contacting members extending toward each other. 25 One of these contacting members is preferably in the form of a bifurcated arm whose base portion is transverse to the axis of rotation of the rotatable contacting member and having two contact parts angular to said 30 base portion and located nearer said axis of rotation than said base portion. The other contacting member is preferably in the form of a rigid arm having a base portion transverse to said axis of rotation and extending 35 from such axis toward the other contacting member, this rigid arm including a contact portion angular to its base portion and receivable between the contacting parts upon the bifurcated contacting member, the contacting portions upon the two contacting 40 members extending toward each other.

The base portion of the bifurcated arm is 45 preferably rigid and the contacting branches of this arm are desirably stiff but are assembled with the base portion in such a manner that each may move with respect to the other and both may move with respect to the base of the arm whereby the switching parts will not be ruptured in the event of 50 their improper assembly or the improper initiation of their assembly. The branches of the bifurcated arm are assembled with the base thereof by means of spring mechanism which maintains the branches and base in 55 normal relation yet which permits the ab-

normal operation of the branches under the circumstances mentioned.

The invention also contemplates the provision of a preferred construction whereby the contact arms, the housings therefor, and 6 the insulating element have their relative positions predetermined so that these parts may be readily and quickly assembled.

I will explain my invention more fully by reference to the accompanying drawings 65 showing the preferred embodiment thereof and in which Figure 1 is a sectional view on line 1—1 of Fig. 2; Fig. 2 is a sectional view on line 2—2 of Fig. 1; Fig. 3 is a view similar to Fig. 2 with parts omitted to reveal 70 details of construction; Fig. 4 is a perspective view showing a contact arm and its branches; Fig. 5 is a perspective view of a part of the structure illustrated in Fig. 4 taken in another direction; Fig. 6 is a perspective view illustrating the component elements of a bifurcated contact arm structure; and Fig. 7 is a perspective view illustrating one of the springs taking part in maintaining the assembly of the base of 80 the contact arm and the branches thereof.

Like parts are indicated by similar characters of reference throughout the different figures.

The rotatable contacting member has a 85 sleeve portion 1 held upon the engine shaft 2 by any suitable means such, for example, as the nut 3 screwed upon the shaft and against a washer 4 in abutting engagement with the inner end of the sleeve, the base 90 portion 5 of this arm branching from one end of the sleeve to be transverse to the axis of rotation of the shaft and of the contacting arm. This contacting arm also includes a contacting portion 6 which is anchored to its base portion as indicated clearly in Fig. 2. There are a number of 95 contacting members successively engageable by and each complementary to the contacting arm 5, 6, when the invention is embodied in a timing switch or has other embodiments effecting the successive closure of independent circuits. Each of these complementary contact members desirably includes a rigid base portion 7 anchored to the casing 8 of 100 the switch by means of a bolt 9 passing through an opening 10 in a part 11 of the switch casing which part is preferably cylindrical and co-axial with the shaft 2. An annular depression 12 is preferably formed 105

upon the interior of the cylindrical casing portion 11 if the casing is formed by a stamping operation so that an annular seat 13 co-axial with the circular opening 10 5 may be formed upon the exterior of the cylindrical casing portion 11 to receive an insulating disk 14. A block 15 of insulating material is disposed between each arm base 7 and the cylindrical portion 11 which has 10 a pocket 16 formed therein for receiving said block and for giving the arm a predetermined position with respect to the timer casing. The disk 14 is in the nature of a nut which is threaded upon the stem of the bolt 15. The block 15 has an opening therethrough through which the stem of the bolt slides, this opening closely engaging the stem of the bolt. As the block 15 is afforded a predetermined position with respect to the 15 timer casing by means of the pocket 16 in the casing, and as the nut 14 is also given a predetermined location with respect to the timer casing, it follows that the bolt 9 receives a predetermined location. In order 20 that the base 7 of each arm may also have a predetermined position with respect to the balance of the fixed parts, I form it with projections or lugs 17 which enter corresponding depressions in the block 15. The 25 assembly of the arm with the casing and the parts that are employed to define the position of this arm with respect to the casing is maintained by means of a metallic lock 30 nut 18.

35 To guard the contact arms that are stationarily mounted upon the casing and thoroughly to prevent electrical connection therebetween, I employ shields 19 of insulating material that are interposed between the 40 bases 7 of the arms and the insulating blocks 15, the stems of the bolts 9 also passing through the insulating shields 19. The adjacent ends of the shields engage each other and are inwardly bent or curled where they 45 engage each other to hold the shields in fixed relation with respect to each other and to serve as insulating elements interposed between the adjacent contact arm bases 7 and parts carried thereby.

50 Each contact arm base is desirably formed with a deflected inner end 7' that is substantially parallel with the axis of the shaft 2. Each arm portion 7' desirably has formed therethrough two openings 20, 21. The contact parts 22, 23 that are carried by each arm base are disposed upon opposite sides of the corresponding arm end 7'. The contact part 22 is provided with openings 24, 25 adapted to register with the openings 20, 21, the contact parts 23 being also provided with openings 26, 27, likewise capable of registry with the aforesaid openings 20 and 21. There are two stiff wire springs 28, 29 bent to have a shape which is somewhat triangular and both co-operating to hold

the contacting parts 22 and 23 in assembly with the arm portion 7'. The end portions 30 of the springs are desirably curled to form closed loops to enable the springs to have extended engagement with the contact 70 part 23. The mid portion of the spring 28 passes through the aligned openings 20, 24 and 26. The mid portion of the spring 29 passes through the aligned openings 21, 25 and 27. The parts of the spring that press upon the contacting part 22 are preferably curled so as to have riding action upon said part, lateral deflection of the parts of the springs being prevented by interposing these curled ends of the springs between 80 lugs 31 formed upon the member 29. The arm end portion 7' is normally closely engaged with the parts 22 and 23 between which it is sandwiched. The portions of the parts 22 and 23 which are actually engaged by the contact arm portion 6 extend beyond the arm portion 7' which thus will not interfere with the operation of the contact 6. The entire base portion 7, including its part 7', of each arm is thus removed 90 from the zone or circle of travel of the contact 6, the contact part 23 being upon the inner side of this circle and the contact part 22 upon the outer side of this circle in the normal assembly of the parts. If the 95 parts are wrongly assembled initially or permanently, the contact 6 may not pass between the contacts 22 and 23 but may be so related thereto as to engage only one or the other and in order that breakage of 100 the parts may not result, the contact parts 22 and 23 will yield and adapt themselves to any positions in which the contact 6 tends to place them so that not only is the breakage of the parts guarded against but the switching function of the structure is not interfered with. The contact parts 22 and 23 diverge at the ends of these parts so that the contacting part 6 may enter therebetween in either direction of rotation thereof. 105 As illustrated, the contacting parts of each pair 22, 23 are movable with respect to their base 7, 7' and with respect to each other in a plane substantially containing the axis of rotation or that is substantially parallel 110 with such axis.

It will be observed that the portions 7, 7', constituting the base portions of the stationary contact members and the base portion 5 of the rotatable contact member, are 115 not in the plane of rotation of the contacting portion 6 at the circle of rotation of this contacting portion and that all of the parts 6, 22 and 23 are, in effect, in the same plane where they engage whereby the contacting portion 6 passes over the base portion 7, 7' irrespective of the direction of rotation of the contacting portion 6. The contacting parts 22 and 23 extend toward the contacting part 6 but not far enough to 130

engage the base portion 5 and likewise the contacting portion 6 extends toward the contacting parts 22 and 23 but not far enough to engage the base portion 7, 7' so that the base portion of one contact or set of contacts cannot be engaged by the contacting portion of the other. In the preferred embodiment of the invention the contact parts 6, 22 and 23 are normally disposed parallel with the axis of rotation of the shaft 2 but the invention is not to be limited to this characteristic.

The structure herein disclosed is more broadly claimed in my co-pending application Serial No. 292,112, filed April 23, 1919.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:

1. An electrical switching device including relatively rotatable contacting members each in the form of an arm having a base portion and a contacting portion angular to the base portion, said contacting portions being in the circle of rotation of the contacting portion of the rotatable contacting member, the contacting portion upon each contacting member extending longitudinally of the axis of rotation toward the base portion of the other contacting member, the base portions of said contacting members being without the plane of rotation of the contacting portion of the rotatable contacting member at the circle of rotation of this contacting portion whereby said base portions are not engaged by said contacting portions.

2. An electrical switching device including relatively rotatable contacting members each in the form of an arm having a base portion and a contacting portion angular to the base portion, said contacting portions being in the circle of rotation of the contacting portion of the rotatable contacting member, the contacting portion upon each contacting member extending longitudinally of the axis of rotation toward the base portion of the other contacting member, the base portions of said contacting portion of the rotatable contacting member at the circle of rotation of this contacting portion whereby said base portions are not engaged by said contacting portions, the contacting part of one of said contacting members being bifurcated portions thereof.

3. An electrical switching device including relatively rotatable contacting members each in the form of an arm having a base portion and a contacting portion angular to the base portion, said contacting portions

being in the circle of rotation of the contacting portion of the rotatable contacting member, the contacting portion upon each contacting member extending longitudinally of the axis of rotation toward the base portion of the other contacting member, the base portions of said contacting members being without the plane of rotation of the contacting portion of the rotatable contacting member at the circle of rotation of this contacting portion whereby said base portions are not engaged by said contacting portions, the contacting portion upon one of said contacting members being movable with respect to the base of this member; and a spring yieldingly holding this contacting portion in relation to its base.

4. An electrical switching device including relatively rotatable contacting members each in the form of an arm having a base portion and a contacting portion angular to the base portion, said contacting portions being in the circle of rotation of the contacting portion of the rotatable contacting member, the contacting portion upon each contacting member extending longitudinally of the axis of rotation toward the base portion of the other contacting member, the base portions of said contacting members being without the plane of rotation of the contacting portion of the rotatable contacting member at the circle of rotation of this contacting portion whereby said base portions are not engaged by said contacting portions, the contacting portion upon one of said contacting members being movable with respect to the base of this member; and a spring yieldingly holding this contacting portion in relation to its base which is turned to extend longitudinally of the axis of rotation and along said movable contacting portion to define the normal position of this contacting portion.

5. An electrical switching device including relatively rotatable contacting members each in the form of an arm having a base portion and a contacting portion angular to the base portion, said contacting portions being in the circle of rotation of the contacting portion of the rotatable contacting member, the contacting portion upon each contacting member extending longitudinally of the axis of rotation toward the base portion of the other contacting member, the base portions of said contacting members being without the plane of rotation of the contacting portions of the rotatable contacting member at the circle of rotation of this contacting portion whereby said base portions are not engaged by said contacting portions, one of said members having two contacting parts movable with respect to each other and the base of this contacting member and between which the contacting part of the other member is receivable; and a spring

yieldingly holding said movable contacting parts in relation to their base.

6. An electrical switching device including relatively rotatable contacting members each in the form of an arm having a base portion and a contacting portion angular to the base portion, said contacting portions being in the circle of rotation of the contacting portion of the rotatable contacting member, the contacting portion upon each contacting member extending longitudinally of the axis of rotation toward the base portion of the other contacting member, the base portions of said contacting members being without the plane of rotation of the contacting portions of the rotatable contacting member at the circle of rotation of this contacting portion whereby said base portions are not engaged by said contacting portions, one of said members having two contacting parts movable with respect to each other and the base of this contacting member and between which the contacting part of the other member is receivable; and a spring yieldingly holding said movable contacting parts in relation to their base which is turned to extend longitudinally of the axis of rotation and between said movable contacting parts to define the normal position of these contacting parts.

7. An electrical switching device including relatively rotatable contacting members each in the form of an arm having a base portion and a contacting portion angular to the base portion, said contacting portions being in the circle of rotation of the contacting portion of the rotatable contacting member, the contacting portion upon each contacting member extending toward the base portion of the other contacting member, the base portions of said contacting members being without the plane of rotation of the contacting portion of the rotatable contacting member at the circle of rotation of this contacting portion whereby said base portions are not engaged by said contacting portions; a casing for the switching device having a pocket formed upon its interior; a block of insulation within this pocket; and a screw coöperating with said block to hold one of said contacting members in relation to the block and the casing.

8. An electrical switching device including relatively rotatable contacting members each in the form of an arm having a base portion and a contacting portion angular to the base portion, said contacting portions being in the circle of rotation of the contacting portion of the rotatable contacting member, the contacting portion upon each contacting member extending toward the base portion of the other contacting member, the base portions of said contacting members being without the plane of rotation of the contacting portion of the rotatable contacting

member at the circle of rotation of this contacting portion whereby said base portions are not engaged by said contacting portions; a casing for the switching device having a pocket formed upon its interior; a block of insulation within this pocket; a screw passing through the base portion of one of said contacting members and said block to the exterior of the casing; and a disk of insulation upon the exterior of the casing through which said screw passes, the casing being provided with a seat upon its exterior for said disk and defining the position thereof.

9. An electrical switching device including relatively rotatable contacting members each in the form of an arm having a base portion and a contacting portion angular to the base portion, said contacting portions being in the circle of rotation of the contacting portion of the rotatable contacting member, the base portions of said contacting members being without the plane of rotation of the contacting portion of the rotatable contacting member at the circle of rotation of this contacting portion whereby said base portions are not engaged by said contacting portions; a casing for the switching device having a pocket formed upon its interior; a block of insulation within this pocket; a screw coöperating with said block to hold one of said contacting members in relation to the block and the casing; and a shield interposed between said block of insulation and the base of the contacting member assembled therewith.

10. An electrical switching device including relatively rotatable contacting members each in the form of an arm having a base portion and a contacting portion angular to the base portion, said contacting portions being in the circle of rotation of the contacting portion of the rotatable contacting member, the contacting portion upon each contacting member extending toward the base portion of the other contacting member, the base portions of said contacting members being without the plane of rotation of the contacting portion of the rotatable contacting member at the circle of rotation of this contacting portion whereby said base portions are not engaged by said contacting portions; a casing for the switching device having a pocket formed upon its interior; a block of insulation within this pocket; a screw passing through the base portion of one of said contacting members and said block to the exterior of the casing; a disk of insulation upon the exterior of the casing through which said screw passes, the casing being provided with a seat upon its exterior for said disk and defining the position thereof; and a shield interposed between said block of insulation and the base of the contacting member assembled therewith.

11. An electrical switching device includ-

- ing relatively rotatable contacting members each in the form of an arm having a base portion and a contacting portion angular to the base portion, said contacting portions being in the circle of rotation of the contacting portion of the rotatable contacting member, the base portions of said contacting members being without the plane of rotation of the contacting portion of the rotatable contacting member at the circle of rotation of this contacting portion whereby said base portions are not engaged by said contacting portions, the contacting portion upon one of said contacting members being movable with respect to the base of this member and in a plane substantially parallel with the axis of rotation; and a spring yieldingly holding this contacting portion in relation to its base. 75
- 10 14. An electrical switching device including relatively rotatable contacting members each in the form of an arm having a base portion and a contacting portion angular to the base portion, said contacting portions being in the circle of rotation of the contacting portions of the rotatable contacting member, the contacting portion upon each contacting member extending longitudinally of the axis of rotation toward the base portion of the other contacting member, the base portions of said contacting members being without the plane of rotation of the contacting portion of the rotatable contacting member at the circle of rotation of this contacting portion whereby said base portions are not engaged by said contacting portions, the contacting portion upon one of said contacting members being movable with respect to the base of this member and in a plane 80 substantially parallel with the axis of rotation; and a spring yieldingly holding this contacting portion in relation to its base which is turned to extend longitudinally of the axis of rotation and along said movable 85 contacting portion to define the normal position of this contacting portion. 90
- 15 12. An electrical switching device including relatively rotatable contacting members each in the form of an arm having a base portion and a contacting portion angular to the base portion, said contacting portions being in the circle of rotation of the contacting portion of the rotatable contacting member, the contacting portion upon each contacting member extending toward the base portion of the other contacting member, the base portions of said contacting members being without the plane of rotation of the 95 contacting portion of the rotatable contacting member at the circle of rotation of this contacting portion whereby said base portions are not engaged by said contacting portions, the contacting portion upon one of said contacting members being movable with respect to the base of this member and in a plane 100 substantially parallel with the axis of rotation; and a spring yieldingly holding this contacting portion in relation to its base which is turned to extend longitudinally of the axis of rotation and along said movable 105 contacting portion to define the normal position of this contacting portion. 110
- 20 13. An electrical switching device including relatively rotatable contacting members each in the form of an arm having a base portion and a contacting portion angular to the base portion, said contacting portions being in the circle of rotation of the contacting portion of the rotatable contacting member, the contacting portion upon each contacting member extending longitudinally of the axis of rotation toward the base portion of the other contacting member, the base portions of said contacting members being without the plane of rotation of the 115 contacting portion of the rotatable contacting member at the circle of rotation of this contacting portion whereby said base portions are not engaged by said contacting portions, one of said members having two contacting parts movable with respect to each other and the base of this contacting member and between which the contacting part of the other member is receivable and in a plane 120 substantially parallel with the axis of rotation; and a spring yieldingly holding said movable contacting parts in relation to their base. 125
- 25 16. An electrical switching device including relatively rotatable contacting members 130

each in the form of an arm having a base portion and a contacting portion angular to the base portion, said contacting portions being in the circle of rotation of the contacting portion of the rotatable contacting member, the contacting portion upon each contacting member extending longitudinally of the axis of rotation toward the base portion of the other contacting member, the 10 base portions of said contacting members being without the plane of rotation of the contacting portions of the rotatable contacting member at the circle of rotation of this contacting portion whereby said base portions are not engaged by said contacting 15 portions, one of said members having two

contacting parts movable with respect to each other and the base of the contacting member and between which the contacting part of the other member is receivable and 20 in a plane substantially parallel with the axis of rotation; and a spring yieldingly holding said movable contacting parts in relation to their base which is turned to extend longitudinally of the axis of rotation 25 and between said movable contacting parts to define the normal position of these contacting parts.

In witness whereof I hereunto subscribe my name this twenty-second day of July 30 A. D., 1919.

CHARLES L. LILLEBERG.
